ACARICIDE AGENT

Horst Werres, Berlin-Charlottenburg, Alfred Czyzewski, Berlin-Tempelhof, and Albert Jager, Berlin-Hermsdorf, Germany, assignors to Schering A.G., Berlin, Germany
 No Drawing. Filed Dec. 28, 1960, Ser. No. 102,080
 Claims priority, application Germany Dec. 28, 1959
 10 Claims. (Cl. 167—30)

The present invention relates to a new acaricide agent, and more particularly to agents for combatting plant damaging spider mites.

Various chemicals have been suggested for combatting plant damaging mites, for example the "red spider." However, in most cases the agent used is only effective against certain development stages of the spider mites so that a complete destruction has not been obtainable prior to the present invention.

It is particularly true that the initial action of the known acaricides is too low, or the same are only effective as ovicides. In addition, it has been particularly difficult to develop acaricides which are both effective and which are compatible with plants.

It is accordingly a primary object of the present invention to provide an acaricidal agent which avoids all of the above mentioned disadvantages of the known agents.

It is another object of the present invention to provide a new acaricide agent which is highly effective against all development stages of spider mites, and which in addition is compatible with plants.

It is yet another object of the present invention to provide a plant-compatible acaricidal agent which is highly effective against all development stages of plant damaging parasites such as the spider mites, etc.

Other objects and advantages of the present invention will be apparent from a further reading of the specification and of the appended claims.

With the above and other objects in view, the present invention mainly comprises an acaricide composition comprising a carrier and a compound of the formula:

wherein R_1 is selected from the group consisting of hydrogen and alkyl, wherein R_2 is alkyl, wherein X_1 is selected from the group consisting of oxygen and sulfur, wherein X_2 is selected from the group consisting of oxygen and sulfur, and wherein R_3 is selected from the group consisting of benzyl and halogen-substituted benzyl radicals.

The substituent R_1 as indicated above is either hydrogen or an alkyl, and when it is an alkyl it is preferably a lower alkyl and most preferably methyl. Likewise, R_2 which is an alkyl is preferably a lower alkyl and most preferably methyl.

As indicated, the substituent R_3 is either benzyl or a halogen-substituted benzyl. Preferably when R_3 is a halogen-substituted benzyl it is a benzyl substituted by one or more halogens, most preferably by chlorine and/or bromine.

The compounds which are used according to the present invention are partially known compounds which can be produced by known methods, for example by the reaction of the corresponding substituted benzyl halogenide with the salt (preferably the alkali metal or ammonium salt) of the corresponding carbamic acid, for example the monothiocarbamic acid or the dithiocarbamic acid.

Compounds of the above general formula wherein the

2

substituents are as set forth in Table 1 below have been found to be particularly effective acaricidal agents:

5

TABLE 1

Compound No.	R_1	R_2	X_1	X_2	R_3
1	Methyl	Methyl	O	S	Benzyl.
2	do	do	O	S	p-Chlorobenzyl.
3	do	do	S	S	Benzyl.
4	do	do	S	S	p-Chlorobenzyl.
5	H	do	O	S	Benzyl.
6	H	do	O	S	p-Chlorobenzyl.
7	Methyl	do	O	O	Benzyl.
8	do	do	O	O	p-Chlorobenzyl.

It should, however, be noted that compounds which are substituted at the nitrogen atom with other alkyl groups or wherein the benzyl radical is substituted by other halogens are also active acaricidal agents.

10

The acaricidal agents of the present invention have been found to be much more effective than O-phenyl esters or S-phenyl esters of carbamic acids or mono-thiocarbamic acids.

15

The compounds of the present invention may be used in various acaricidal dosages in application thereof to an area subject to spider mites attack in order to combat such spider mites attack, and the range of dosage may vary quite considerably in view of the fact that very low dosages are effective, and very high dosages are compatible with continuation of the plant life.

20

The agents can be applied with any carrier commonly used for agents of this type, and in any form, for example in the form of a suspension, emulsion, powder, solution, aerosol, or the like. The agents may be applied alone or in admixture with other insecticides, fungicides, or the like.

25

Among the suitable liquid and solid carriers for the compounds of the present invention are water, mineral oils, organic solvents, emulsifying or suspending agents, bentonite, fuller's earth, gypsum, lime, diatomaceous earth, pyrophyllite, silica, talc, chalk, or the like. Emulsifiers, wetting agents or binding agents may be added to the preparations as well as carrier gases, odoriferous

30

substances, substances for attracting, or repellants. As indicated the preparations can be in the form of dust, agents for spreading, granulates, for spraying, atomizable liquids, aerosols, etc.

35

The following examples are illustrative of preparations prepared in accordance with the present invention. The scope of the invention is not, however, meant to be limited to the specific details of the examples:

Example 1

40

PREPARATION OF A WETTABLE POWDER FOR SPRAYING

A mixture is prepared of:

50% N,N-dimethylthiocarbamic acid benzyl ester
 10% lignin sulfonic acid (calcium salt)
 5% sodium salt of sulfonated ethylmethylethylamide
 3% urea-formaldehyde condensate
 2% starch decomposition product
 30% carrier (aluminum silicate)

45

Example 2

50

PREPARATION OF AN EMULSION CONCENTRATE

A preparation is prepared of:

20% N,N-dimethylthiocarbamic acid benzyl ester
 1% of a mixture of oil soluble sulfonates and polyoxyethylene products
 89% solvent naphtha

The activity of the new acaricidal agents of the present invention is apparent from Table 2 below:

TABLE 2

Preparation of compound of Table 1	Percent active substance	Percent action after number of days indicated					
		1		3		7	
		A+N L	A+N L	A+N L	E		
No. 1-----	0.1-----	100	100	100	100	100	100
	0.04-----	100	100	100	100	100	100
No. 2-----	0.1-----	100	100	100	100	100	100
	0.04-----	98	95	100	100	100	100
No. 3-----	0.1-----	100	100	100	100	100	100
	0.04-----	80	70	90	100	100	100
No. 4-----	0.01-----	90	90	100	100	100	100
	0.04-----	80	70	90	100	100	100

The tests were carried out in such manner that bush beans which were infested with bean spider mites of all stages of developments (adults—A), (nymphs—N), (larvae—L) and (summer eggs—E) were treated with aqueous suspensions of the agents indicated. The acaricidal effect was determined after 1, 3 and 7 days.

The above figures are the result of 15 parallel series of experiments under equal conditions.

The amount of the active substance of the compounds of this invention which are used in the preparations for combatting spider mites may vary in ample limits. It depends on the kind of formulation, the kind of application, the desired measure of control and the kind of the pests to be combatted. Depending on the kind of preparation the amount of active substance in the agent may be about 0.1 to 90 percent by weight. The agents may be applied in concentrations as low as 0.01 percent by weight. Usually good results are received by concentrations between about 0.025 and 10 percent in liquid or solid carriers. For special purposes higher concentrations may be desired for instance as high as about 20 percent.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. The method of killing acarids, which comprises contacting the acarids with a compound of the formula:

wherein R_1 is selected from the group consisting of hydrogen and alkyl, wherein R_2 is alkyl, wherein X_1 is selected from the group consisting of oxygen and sulfur, wherein X_2 is selected from the group consisting of oxygen and sulfur, and wherein R_3 is selected from the group consisting of benzyl and halogen-substituted benzyl radicals.

2. The method of combatting spider mites attack, which comprises applying to an area subject to spider mites attack a compound of the formula:

wherein R_1 is selected from the group consisting of hydrogen and alkyl, wherein R_2 is alkyl, wherein X_1 is selected from the group consisting of oxygen and sulfur, wherein X_2 is selected from the group consisting of oxygen and

sulfur, and wherein R_3 is selected from the group consisting of benzyl and halogen-substituted benzyl radicals.

3. The method of combatting spider mites attack, which comprises applying to an area subject to spider mites attack a compound of the formula:

10 wherein R_3 is benzyl.

4. The method of combatting spider mites attack, which comprises applying to an area subject to spider mites attack a compound of the formula:

wherein R_3 is p-chlorobenzyl.

20 5. The method of combatting spider mites attack, which comprises applying to an area subject to spider mites attack a compound of the formula:

wherein R_3 is benzyl.

6. The method of combatting spider mites attack, which comprises applying to an area subject to spider mites attack a compound of the formula:

35 wherein R_3 is p-chlorobenzyl.

7. The method of combatting spider mites attack, which comprises applying to an area subject to spider mites attack a compound of the formula:

wherein R_3 is benzyl.

40 8. The method of combatting spider mites attack, which comprises applying to an area subject to spider mites attack a compound of the formula:

50 wherein R_3 is p-chlorobenzyl.

9. The method of combatting spider mites attack, which comprises applying to an area subject to spider mites attack a compound of the formula:

wherein R_3 is benzyl.

60 10. The method of combatting spider mites attack, which comprises applying to an area subject to spider mites attack a compound of the formula:

wherein R_3 is p-chlorobenzyl.
